UNITED STATES PATENT OFFICE

102,115

DESIGN FOR A BUILDING

Robert J. Shaw, Philadelphia, Pa.

Application February 24, 1936, Serial No. 61,323

Term of patent 14 years

To all whom it may concern:

Be it known that I, Robert J. Shaw, a citizen of the United States, residing at Philadelphia, in the county of Philadelphia and State of Pennsylvania, have invented a new, original, and ornamental Design for a Building, of which the following is a specification, reference being had to the accompanying drawings, forming part thereof.

The present invention is a continuation in part of my copending application for U. S. patent, filed August 3, 1935, Ser. No. D-57,932.

In the drawings:

Fig. 1 is a side elevation of a building illustrating my new design;

Fig. 2 is an end elevation with parts broken away of the same structure; and

Fig. 3 is a plan view thereof.

I claim as my invention:

The ornamental design for a building as shown and described.

ROBERT J. SHAW.
